Des. 225,663

Patented Dec. 26, 1972

225,663

MODEL RACING CAR

Josef Helmut Karasek, Lenggries, Germany, assignor to
McNamara Racing K.G., Urtmuhlweg, Germany

Filed Aug. 12, 1971, Ser. No. 171,415

Claims priority, application Great Britain Feb. 18, 1971

Term of patent 7 years

Int. Cl. D21—01

U.S. Cl. D34—15

FIG. 1 is a top plan view of a model racing car showing my new design;

FIG. 2 is a front elevational view thereof;

FIG. 3 is a left side elevational view thereof, the right side being substantially similar thereto;

FIG. 4 is a rear elevational view thereof.

I claim:

The ornamental design for a model racing car, as shown and described.
